UNITED STATES PATENT OFFICE

2,370,284

ADHESIVE TRANSFERRING MECHANISM

James Balton, Baltimore, Md., assignor to Maryland Baking Company, Inc., Baltimore, Md., a corporation of Maryland

Original application February 19, 1941, Serial No. 379,727. Divided and this application July 28, 1942, Serial No. 452,633

5 Claims. (Cl. 91—47)

My invention relates generally to machines for forming frusto-conical or conical, tapering or cylindrical jackets, and in particular it has for its object to provide a new and improved mechanism for applying adhesive to the jackets while they are held flat on the conveyor carriages.

A further object is to provide such mechanism, operating in harmony with the other mechanisms of the machine, to apply the adhesive while the carriage is moving past the glue applying station.

Another object is to provide a continuously moving glue applying means which includes intermittently operated applicators and means to effect their operations in time with the movement of the blank carriage.

Other objects will in part be obvious and in part will be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a front elevation of so much of the jacket forming machine as is necessary to illustrate the position and relation of the adhesive applying mechanism proper to the carriages and conveyor.

Fig. 2 is a side elevation of the turret unit.

Fig. 3 is a horizontal section on the line 3—3 of Fig. 2.

Fig. 4 is an edge view of one of the applicators.

Fig. 5 is a side elevation of the same.

Fig. 6 is a side elevation showing the other side of the applicator.

In the drawings, in which like numbers of reference indicate like parts in all the figures, the numerals used are the same as those used to indicate the same parts shown in my application Ser. No. 379,727, filed February 19, 1941, of which this application is a division.

In general, the jacket forming machine includes a frame having longitudinal beams 4 and 5 and uprights 3. An endless chain 17 has link brackets 22 on which the bases 23 of the jacket shaping units are mounted. Each jacket shaping unit includes a blank carriage 61 and a mandrel 55. Each carriage 61 has a flat top surface 62 on which the blank B lies.

The blank B is held from shifting in its own plane while on the carriage by means of spaced pins 63. There is a contact cylinder 65 on each carriage to cooperate with holding fingers 41 in applying the blank to the mandrel. As the elements of the folding mechanisms other than the carriages are not necessary to an understanding of the present invention, a detailed description

of the same is superfluous in this specification.

By referring now more particularly to Figs. 1, 2 and 3, it will be seen that in an upper bearing 150 and a lower bearing 168 is mounted a vertical shaft 151 to which is secured the hub 152 of a turret that comprises the said hub, the upper and lower discs 153, 154 respectively, and the parts carried by the discs. Such parts consist of four sets of dauber devices arranged radially 5 90° apart. Each dauber device consists of two rods 155 passing vertically through bearing holes in the discs and connected together at the top by a cross-head or plate 156 on which is secured a bevelled block 166. Beneath the disc 154 the rods 155 carry stop collars 157 and angle heads 162, to which heads the daubers 163 (rubber or other suitable material) are mounted by means of clamp plates 164 and screws. Each dauber 163 has one or more glue spotters 165.

20 The cross-heads 156 are vertically adjustably held by cotter pins 160 and the lower disc 154, and tend constantly to raise the daubers.

25 A fixed cam 167 is engaged by the bevelled blocks one at a time as the turret turns in order to depress the daubers onto the rollers 195 of the glue pot 192. The pot 192 is removably held on a bracket 190 by clamp screws 191.

30 The shaft 193 on which the rollers 195 are mounted is driven from the conveyor drive shaft (not shown). The amount of glue on the rollers 195 is regulated by an adjustable slide or plate 196 whose inner edge lies adjacent the rollers 195, the space between that edge and the rollers governing the thickness of the film of glue on 35 the tops of the rollers.

At its upper end the shaft 151 has a bevel gear 169 that meshes with a bevel gear 171 on a cross shaft 170. The shaft 170 is driven from a continuously rotating rotary shaft 243 and bevel 40 gears 244.

45 There is also a spur gear 177 secured on shaft 170 to mesh with a pinion 178 on a stub shaft 179. On this stub shaft is mounted a cam 180 which cooperates with a cam-engageable nose 183 on a rocker arm 182 that is pivoted to a support 181 and is connected by an adjustable connecting rod 188 with an arm 184 that is pivoted at 185 to a suitable support and carries a tappet 187 to engage the bevelled blocks 166 at proper 50 times, as will later more fully appear. 186 is an arm adjusting screw.

55 Mounted behind the turret is a U-shaped bar 199 whose ends 200 are forked to receive the stud bolts 314 that adjustably secure the supports 201 to the bar. The supports 201 carry one or more grooved discs 202 around which taut wires 203 are passed and have their ends anchored as at 204. These wires lie horizontally across the paper blanks on the carriages as the carriages pass the turret at what might con-

veniently be termed the glue-applying station of the machine.

Just beyond the glue-applying station is a mandrel wiping device consisting of a bracket 205 carrying a wiper 206. As the mandrels pass this wiper they are being forced outwardly (forwardly) under the wiper, which wiper is so positioned that the entire length of the flat surface 56 will be wiped clean.

Operation

The blanks B are placed on the carriages (in the complete machine) by suitable means (not shown). The carriages 61 travel with the conveyor 17 from left to right in Fig. 1.

The carriages with the blanks deposited thereon then travel beneath the wires 203, past the glue-applying station. The daubers 163 of the turret take up glue as they pass over the glue wheels 195 by being forced an instant pressed down in contact with the fixed cam 167. When a dauber comes into proper position over a carriage so as to be directly over and line up with the right-hand side of the blank on the carriage, the lever 184 is forced down for an instant and tappet 187 engages the bevelled block 166 of that dauber to stamp the glue on the paper.

The wires 203 are stretched taut and prevent the blanks from sticking to the daubers 164 as the daubers lift up after "stamping" the glue on the blanks.

After the glue has been applied the blanks are applied to the mandrels and brought to shape for use in any suitable way, preferably in the manner and by the means disclosed in my original application aforesaid, but as that means is not a part of the present application, detailed description thereof is not necessary to an understanding of the subject matter of this application.

From the foregoing description, taken in connection with the accompanying drawings, it is thought that the construction, operation and advantages of the invention will be clear to those skilled in the art to which it relates.

What I claim is:

1. In a machine of the character described, wherein glue is transferred from a stationary glue pot to a blank on a travelling carriage, a glue transfer device comprising a rotatable shaft, a hub carrying an upper disc and a lower disc, said discs each having at least one pair of vertically aligning bearing holes, a pair of rods in said holes and projecting above the upper disc and below the lower disc, a dauber mounted on the lower ends of said rods, a cross-head connecting the upper ends of said rods together whereby said rods may be moved up and down in unison, springs on said rods constantly urging the rods upwardly, a block on said cross-head, and quick-acting cams for engagement by said block as said shaft is rotated to instantaneously depress said rods and dauber at predetermined times.

2. In a machine of the character described, wherein glue is transferred from a stationary glue pot to a blank on a travelling carriage, a glue transfer device comprising a rotatable shaft, a hub carrying an upper disc and a lower disc, said discs each having at least one pair of vertically aligning bearing holes, a pair of rods in said holes and projecting above the upper disc and below the lower disc, a dauber mounted on the lower ends of said rods, a cross-head connecting

the upper ends of said rods together whereby said rods may be moved up and down in unison, springs on said rods constantly urging the rods upwardly, a block on said cross-head, in combination with a fixed quick-acting cam for engagement by said block when said dauber is over the glue pot to instantaneously depress the dauber and cause it to gather glue.

3. In a machine of the character described, 10 wherein glue is transferred from a stationary glue pot to a blank on a travelling carriage, a glue transfer device comprising a rotatable shaft, a hub carrying an upper disc and a lower disc, said discs each having at least one pair of vertically aligning bearing holes, a pair of rods in said holes and projecting above the upper disc and below the lower disc, a dauber mounted on the lower ends of said rods, a cross-head connecting the upper ends of said rods together whereby said rods may be moved up and down in unison, springs on said rods constantly urging the rods upwardly, a block on said cross-head, in combination with a quick-acting fixed cam for engagement by said block when said dauber is over the glue pot to instantaneously depress the dauber and cause it to gather glue, and a second quick-acting device to instantaneously depress the dauber when it is over a predetermined part of the carriage to transfer the glue to the blank.

20 4. In a machine of the character described, 30 wherein glue is transferred from a stationary glue pot to a blank on a travelling carriage, a glue transfer device comprising a vertically disposed rotatable shaft, a hub carrying an upper disc and a lower disc, said discs each having at least one pair of vertically aligning bearing holes, a pair of rods in said holes and projecting above the upper disc and below the lower disc, a dauber mounted on the lower ends of said rods, a cross-head connecting the upper ends of said rods together whereby said rods may be moved up and down in unison, springs on said rods constantly urging the rods upwardly, a block on said cross-head, cams for engagement by said block as 35 said shaft is rotated to depress said rods and dauber at predetermined times, and means to effect continuous travel of said carriage and continuous rotation of said shaft.

5. In a machine of the character described, 50 wherein glue is transferred from a stationary pot to a blank on a horizontally travelling carriage: a glue transfer device comprising a vertically rotatable shaft, a hub on said shaft and carrying an upper disc and a lower disc each having a hole, a rod vertically reciprocably mounted in said holes, a spring means constantly tending to lift said rod, means limiting the upward movement of said rod to a predetermined position, a dauber on said rod, an inverted V-shaped cam 55 carried by said rod, a fixedly located V-shaped trip-cam positioned to be engaged by said inverted V-shaped cam at times to instantaneously depress said rod to cause said dauber to pick up glue, a pivoted lever having a tappet at one end to engage said inverted V-shaped cam at another time to depress said rod to cause said dauber to deliver the glue to the blank, spring means holding said lever in a normal position, and a quick-acting cam for actuating said lever 60 for effecting the application of the glue to the blank.

JAMES BALTON.
